CLAIM

The ornamental design for a weightlifting grip, as shown and described.

DESCRIPTION

FIG. 1 is a right side view of the weightlifting grip in accordance with the present invention, shown in a condition in use.

FIG. 2 is a Perspective 3/4 Top View of the weightlifting grip in accordance with the present invention, shown as used on a dumbbell.

FIG. 3 is another perspective view of the weightlifting grip in accordance with the present invention.

FIG. 4 is a Top Plan View of the weight lifting grip in accordance with the present invention.

FIG. 5 is a Bottom Plan View of the weight lifting grip in accordance with the present invention.

FIG. 6 is another right side view of the weightlifting grip in accordance with the present invention.

FIG. 7 is a Left Side View of the weight lifting grip in accordance with the present invention.

FIG. 8 is a Right End View of the weight lifting grip in accordance with the present invention; and,

FIG. 9 is a Left End View of the weight lifting grip in accordance with the present invention.

The broken lines shown in FIG. 1 are for the purpose of illustrating environmental structure, which form no part of the claimed design.
